COASTER OR THE LIKE

Rubin Shatkin, Long Branch, N. J., assignor to Crest Silver Mfg. Co. Inc., Matawan, N. J., a corporation of New Jersey

Application October 6, 1949, Serial No. 5,336

Term of patent 3½ years

(Cl. D44—10)

To all whom it may concern:

Be it known that I, Rubin Shatkin, a citizen of the United States, residing at the city of Long Branch, in the county of Monmouth and State of New Jersey, have invented a new, original, and ornamental Design for a Coaster or the like, of which the following is a specification, reference being had to the accompanying drawings, forming part thereof, wherein Fig. 1 is a top plan view of a coaster showing my new design;

Fig. 2 is a side elevational view and Fig. 3 is a vertical sectional view thereof taken at line 3—3 in Fig. 1.

I claim:

The ornamental design for a coaster or the like, substantially as shown.

RUBIN SHATKIN.
